UNITED STATES PATENT OFFICE.

STEPHEN E. GRIGGS, OF SEATTLE, WASHINGTON.

VACUUM APPARATUS.

No. 878,723.

Specification of Letters Patent.

Patented Feb. 11, 1908.

Application filed February 27, 1907. Serial No. 359,568.

To all whom it may concern:

Be it known that I, STEPHEN E. GRIGGS, a citizen of the United States, residing at Seattle, in the county of King and State of Washington, have invented certain new and useful Improvements in Vacuum Apparatus, of which the following is a specification, reference being had therein to the accompanying drawing.

10 This invention relates to therapeutical apparatus and particularly to appliances for giving local treatment to affected parts of the human body by the application to the surface thereof of a partial vacuum induced through the medium of "vacuum cups".

15 The principle of this method of treatment is well-known and may be briefly described as follows: In cases of rheumatism, lumbago and other acute inflammatory conditions much relief is rendered the patient by the lessening of the air-pressure from the diseased portion of the body and a favorable condition for the restoration of the normal state of health is induced by the resultant hyperemia or congestion of blood to that part through the application of vacuum cups of suitable shapes to conform to the various parts of the body and from which the air has been rarefied to effect the required tension.

30

In the relief of some abnormal conditions, such as rheumatism or lumbago above mentioned, where the seat of trouble may extend over a relatively large area, the vacuum cups may be of considerable dimensions. The present practice of rarefying or exhausting the air from the cups is by means of suction pumps and they are found to be unsatisfactory as requiring the attention of the physician at a time when his observation should be upon the patient.

With the apparatus embodying my invention no tedious pumping is required to place the same in operation, the pressure of the thumb of the operator controlling the amount of tension desired within the cups; its compactness and size enabling it to be placed in any convenient place suitable to accomplish the purposes intended; and it can be manufactured at small cost to permit of its use not only in public clinics and hospitals but in the private office of the physician.

With the aforesaid and other objects in view, the invention consists in the novel

construction and combination of parts as will be hereinafter described and claimed.

The accompanying drawing is a perspective view of apparatus embodying my invention.

Referring to the drawing, the numeral 3 indicates a tubular vessel impervious to the air and of about two or three feet in length and is desirably made of glass in order to disclose the height of liquid therein. Said vessel is secured, as by wall attachments 4, in a vertical position and at an elevation sufficient to supply a pressure from the contained liquid necessary to accomplish the purposes for which intended.

The vessel 3 is provided with openings 5 and 6 for the intake and discharge of the liquid and likewise with an opening 7 which is communicatively connected by a tube 8 with the cup appliance. Said discharge opening is positioned at the extreme bottom of the vessel so that the entire liquid contents may be withdrawn; while the opening 7 is continued upwardly into a bent tube 7' to make the entire length of the vessel available to the reception of the water.

At the openings 5 and 6 are provided nipples 5' and 6', or their equivalents, for making connection with flexible tubing 9 and 10, respectively, with a water supply faucet 11 and with a receptacle to receive the waste water from the apparatus. The faucet 11 serves to control the admission of water to the vessel and a valve 12 is provided in the tube 8 to regulate the flow of air therethrough in both the filling and emptying of the vessel of water.

13 is a supplementary closure included in the tube 10 but may be omitted if desired.

The operation of the invention is as follows: The vessel 3 is first charged with water by opening air valve 12 and the faucet 11 whereupon the same are closed. The cup is now applied to the part of the patient to be treated so that the cup rim will be in complete contact with the flesh about the affected part and thus prevent any air extraneous of the cup entering the latter. By opening the valve or valves 12 and 13 the air within the cup is released and partially withdrawn through the escape of the water through the waste pipe and is continued until all of the water has been discharged from the vessel or enough to establish the

required rarefaction of the air within the cup, the flow of water therefrom being controlled by the manipulation of the valve 12.

In practice a portion only of the water contained in the vessel is withdrawn for each application of the cup. An extreme test would cause an intense congestion of blood at the point while in actual medical practice a slight pressure is all that is desired. With this apparatus the patient in many cases would desirably manipulate the valve 12 himself to secure the comfortable degree of pressure.

Vacuum cups are commonly made with a portion of tubing attached and provided with a valve, as shown at 14. Two or more cups can thus be successively applied by inducing the required degree of pressure in a cup and closing the valve of the same; the valve 12 being likewise closed the tube 8 may be removed and applied to a second cup and as many more as desired.

Having described my invention what I claim as new and desire to secure by Letters-Patent, is—

1. In an exhausting apparatus, comprising in combination with a cup, of a closed vessel, a tube communicatively connecting said cup with the top of said vessel, a tube making communicative connection between the bottom of said vessel and a supply of water under sufficient head to fill said vessel, a liquid discharge opening in the bottom of said vessel, and a valve, or its equivalent, for each of said tubes.

2. In an exhausting apparatus, the combination with a cup, of a vessel having a water inlet tube at the bottom, a flexible tube leading from the vessel adjacent of its top to the cup to be exhausted, an outlet for said vessel, and means to control the inflow and discharge of the water from the respective tube and outlet.

3. In an exhausting apparatus, the combination with a cup, of a vessel, an inlet for supplying water to drive the air out of the vessel prior to the exhausting operation, an outlet to said vessel, and means for control-

ling the evacuation of water from the vessel and whereby the air is exhausted from the cup.

4. In an exhausting apparatus, in combination with a cup, a vessel disposed at an elevation sufficient to maintain a barometric column of a liquid employed which when withdrawn will produce a desired vacuum in the cup, an inlet to supply said liquid to the vessel, a flexible tube connecting the vessel adjacent of its top with the cup from which the air is to be exhausted, and means open at all times to withdraw the liquid from the vessel whereby the exhaustion of the air from the cup is accomplished.

5. In an exhausting apparatus, a single vessel, means to dispose said vessel at a determined elevation, means for connecting said vessel with a source of fluid supply under pressure, means at the bottom of said vessel to enable the fluid to be withdrawn therefrom, a vacuum cup, and means connecting said cup with the top of said vessel.

6. In combination with a water supply faucet, and the bowl thereof a vessel secured at a point higher than said faucet, a tube connecting said faucet with the lower end of said vessel, an exhaust tube open at all times leading from the lower end of said vessel to said bowl, and a third tube leading from the top of said vessel and having a vacuum cup connected thereto.

7. In an exhausting apparatus, a vessel of cylindrical form for containing liquid, means for securing said vessel to a support so that the same may be secured at a determined elevation, a pair of flexible tubes leading from separate points at the bottom of said vessel, and a third tube leading from the top of said vessel and having a cup connected thereto.

In testimony whereof I affix my signature in presence of two witnesses.

STEPHEN E. GRIGGS.
